LEHMAN H. CRANDALL, OF LOS ANGELES, CALIFORNIA.

BELT-BUCKLE.

1,347,324.

Specification of Letters Patent. Patented July 20, 1920.

Application filed October 6, 1919. Serial No. 328,671.

To all whom it may concern:

Be it known that I, LEHMAN H. CRANDALL,
a citizen of the United States, residing at
Los Angeles, in the county of Los Angeles
5 and State of California, have invented new
and useful Improvements in Belt-Buckles,
of which the following is a specification.

This invention relates to a buckle and particularly pertains to a buckle of the type commonly employed on garment supporting belts.

It is the object of this invention to provide a belt buckle for attaching the ends of a belt embodying a slide grip whereby the free end portion of a belt may be quickly and securely clamped in any desired position relative to the other end portion of the belt, and in such manner as to entirely eliminate any possibility of inadvertent loosening of the belt, but which will permit of ready disengagement and adjustment.

Another object is to provide a belt buckle of the sliding clamp type, so formed as to effect a tight engagement with a belt without mutilating same and which tends to grip the belt more securely as expanding strain on the belt increases.

30 A further object is to provide a belt buckle embodying a pair of gripping members 35 slideable longitudinally relative to each other between which the free end of a belt may be interposed, and a construction whereby said members may be caused to have a wedge actuated clamping action upon the belt to oppose movement of the belt, but which can be readily positioned to permit free movement of the belt.

Other objects will appear hereinafter.

The invention is illustrated in the accompanying drawings in which:

Figure 1 is a perspective view of the belt buckle showing it as applied;

Fig. 2 is a view of the belt buckle as seen from the rear and in a detached position.

45 Fig. 3 is a detail in longitudinal section, showing the gripping members in their open position.

Fig. 4 is a view in longitudinal section, showing the gripping members in their closed or gripping position.

More specifically, 5 indicates a back plate member which is designed to be rigidly secured to one end of a belt 6 and will hereafter be referred to as a fixed gripping member; the plate being detachably connected to the belt by means of a toothed

clamp 7 such as is commonly employed on belt and suspender fastenings and the like. This clamp 7 is pivotally mounted on the plate by means of trunnions 8 formed on the edges of the clamp and projecting through perforations 9 in ears 10 arranged at the inner terminal of the plate. The ears 10 project inwardly at right angles to the plate and are formed in continuation of inwardly projecting marginal flanges 11 extending throughout the longitudinal edges of the plate.

The flanges 11 form a guide bearing for a
slidable gripping member 12, embodying a 70
plate extending over the outer face of the
plate 5 and having turned marginal flanges
13 projecting over the flanges 11 and which
flanges are formed intermediate their ends
and about midway of the length of the slid-
able gripping member with turned tangs
14 projecting over and around the edges of
the flanges 11 in slidable engagement with
the latter. 75

In order to effect a clamping action between the members 5 and 12, the flanges 11 are formed tapered, that is with their edges arranged on an incline relative to the outer face of the plate; the edges of the flanges sloping outwardly toward the outer end of the plate 5, as indicated at 15, in such manner that when the slid able member is advanced toward the outer end of the fixed member with the tangs 14 riding on the flanges, the plate portion of the slid able member will be advanced inwardly toward the plate portion of the fixed member. The portions of the flanges 11 adjacent to the inner attached end of the fixed member are comparatively narrow, so that when the slid able member is retracted to position the tangs 14 on the narrow portions of the flanges, the face plate may be disposed in such spaced relation to the plate 5 as to permit ready insertion and removal of the free end of the belt.

In constructing the buckle, the members 5 and 12 are formed complete, with the in-turned tangs spaced such distance from the inner wall of the face plate that these tangs 105 may be passed over the ears 10 to position the tangs on the flanges. The outer end of the plate 5 is turned inwardly to form an end flange 16 which serves as a stop to limit the outward movement of the slidable member. The clamp 7 is put in place after the 110 slidable member is positioned on the fixed

member and serves as a stop to limit the inward movement of the slidable member.

As a means for facilitating the spacing or outward movement of the slidable member on retraction thereof, the inner ends of the flanges 13 are formed with inclines 17 and the trunnions 8 are formed of such length as to project sufficient distance beyond the outer faces of the ears 10 as to be disposed in such position as to engage the inclined faces 17 on retraction of the slid- 10 able member and cause the inner end of the latter to move outwardly.

As a means for confining the gripping action between the members 5 and 12 to a relatively narrow area and to a space intermediate the ends of the members, the plate portions of the members 5 and 12 are formed on curvatures of different arcs; the plate 20 portion of the member 5 being formed on an arc having a radius less than that on which the plate portion of the slidable member is formed, as particularly shown in Fig. 4 so that the middle portion of the 25 inner or back plate member will extend closer to the inner face of the outer or slid- able member. By this construction the point of engagement with the belt will be concealed behind the outer slidable member so that in event this portion of the belt 30 wears by reason of engagement of the buckle therewith, the worn portion will be hidden behind the outer slidable member.

In the operation of the invention, the 35 slidable member 12 is retracted, as shown in Fig. 3, to space the face portion thereof from the outer face of the fixed member 5, and the free end 18 of the belt is inserted through the space thus formed, as shown 40 in Fig. 1, whereupon the slidable member is advanced as shown in Fig. 4 to grip the belt under the wedge action of the inclined faces 15 on the tangs 14. By this arrangement a pull on the belt in the direction to 45 advance the slidable member tends to move the latter into closer and tighter engagement with the belt, thereby effectively preventing slipping of the latter.

When it is desired to loosen the belt, the 50 slidable member is retracted such distance on the fixed member as to release the belt, whereupon the latter may be detached or adjusted to any desired position. The com- 55 paratively flat engagement of the belt be- tween the gripping members avoids mutila-

tion of the belt and the readiness with which the slidable gripping member may be advanced and retracted enables quick attachment, adjustment and removal of the belt.

60

I claim:

1. In a belt buckle, a curved fixed gripping member, a curved slidable gripping member having a face plate normally spaced from the fixed member thereon, said 65 face plate formed with a less curvature than that of the fixed gripping member, and means whereby advancing said slidable gripping member longitudinally on said fixed gripping member will operate to move the 70 face plate toward the fixed member to grip a belt interposed between said members.

2. In a belt buckle, an arcuate fixed gripping member having tapered longitudinally extending marginal flanges, and a slidable 75 arcuate gripping member having inturned tangs riding on said tapered flanges, said slidable gripping member being formed on a curvature less than that of the fixed grip- 80 ping member.

3. In a belt buckle, an arcuate fixed gripping member having tapered longitudinally extending marginal flanges, a slidable arcuate gripping member having inturned tangs riding on said tapered flanges, said slidable 85 gripping member being formed on a curvature less than that of the fixed gripping member, projections on said fixed gripping member, and inclined faces on said slidable gripping member adapted to ride against 90 said projections to move said slidable gripping member outwardly relative to the fixed gripping member.

4. In a belt buckle, an arcuate fixed gripping member having tapered longitudinally 95 extending marginal flanges, a slidable arcuate gripping member having inturned tangs extending over and around the edges of said tapered flanges, means at the terminations of said tapered flanges for operating with 100 the tangs to prevent disengagement of the tangs from the flanges, projections on the fixed gripping member extending from the sides thereof, and inclined faces on said slidable gripping member adapted to ride 105 against said projections to move the slidable gripping member outwardly relative to the fixed gripping member.

LEHMAN H. CRANDALL.
